Inventor:

BRUNO EBERT by
Karl Kiertel Atty

UNITED STATES PATENT OFFICE

BRUNO EBERT, OF LOSSNITZ, GERMANY

DETACHABLE COLLAR

Application filed March 7, 1930, Serial No. 434,104, and in Germany June 15, 1928.

My invention relates to improvements in detachable collars of the folded type and more especially to so-called double collars for men's wear which consist of starched 5 linen cloth, cotton, silk or like woven material.

As a rule collars of this type are carefully shaped by the manufacturers so as to provide ample space for the necktie to be easily 10 inserted between the outer flap and the neck band of the collar, and to be freely moved around, while the ends of the necktie are tied in a bow or knot.

However—as a matter of fact—collars 15 which are repeatedly washed and ironed will thereby gradually lose their proper shape i. e. showing a tendency to hold firmly clamped the inserted neck tie and rendering it an annoying task to slide it into its proper 20 place.

The principal object of this invention is to overcome the said drawback and to provide a double collar of improved design which is substantially proof against losing its initial 25 shape through washing and ironing.

With this object in view the neckband and the fold over flap of the collar are joined together by a seam or junction line which is arc- or bow-shaped when the collar is unfolded and laid out flat; reinforcing threads 30 being provided within the neck band in such like position as to represent the chord of said arc, said threads running longitudinally through the neck-band and being adapted to 35 act as bracing members, safeguarding the arc-shaped seam against being straightened out and levelled during ironing and kindred stretching operations. The neck-band may be cut from woven material composed of alternate closely woven strips and adjacent 40 strips of lighter weave.

The nature and scope of my invention are briefly outlined in the appended claim and will be more fully understood by the following specification taken together with the accompanying drawings in which

Fig. 1 shows a double collar in unfolded condition while being ironed,

Fig. 2 is a cross section through the folded 50 collar.

The collar consists of the outer flap 10 and the neckband which comprises two sections, the lower section 22 containing the button holes 30, 31, 32 and being made of material which is pliable enough to facilitate manipulation, i. e. attaching and buttoning, whilst the upper section 21 of the neckband portion, joining the outer flap 10 along the top edge 11 of the collar, is preferably made of a heavier material, as diagrammatically indicated in the drawings by the differently directed cross hatchings.

As seen in Fig. 1 the top edge 11 at which the neckband and the fold over flap 10 are joined together is curved or arc-shaped, when the collar is unfolded and laid out flat. Within the neckband of the collar a plurality of reinforcing threads 23a are provided running longitudinally therethrough in a straight line; the latter are functionally associated with the said arc-shaped top edge 11 or seam line and represent as to their position and function a chord or bracing member of the said arc.

To wit: By the said bracing member the 75 arc-shaped seam 11 is safeguarded against deformations viz. against being flattened and levelled by ironing and kindred operations, during which the collar is subjected to comparatively heavy pulling, stretching and 80 other stresses tending to deform the collar.

My experiments have shown that by reinforcing the neck band in the manner shown any undue and premature deformations of the collar through ironing entailing troubles 85 in putting on neck ties are effectively prevented.

Various changes and modifications may suggest themselves to those skilled in this field of manufacture as to the design of improved collars as described and the assemblage of their component parts, without substantially departing from the spirit of my invention and sacrificing any advantages obtained thereby.

I prefer to have the said reinforcing threads 23a directly woven into or interlaced with the material of which the neck bands of my improved collars are made.

What I claim is:

Detachable double collar of the folded type comprising in combination a neck-band and an outer flap which are joined together by an arc-shaped seam when the collar is unfolded and laid out flat, a plurality of reinforcing threads being so provided within the neck-band as to represent a chord of said arc, said threads running longitudinally through the neck-band and being adapted to safeguard the said arc-shaped seam against being straightened during ironing and kindred stretching operations.

In testimony whereof I have signed my name to this specification.

BRUNO EBERT.
